UNITED STATES PATENT OFFICE.

WILLIAM BILLINGS, OF DOVER, ILLINOIS.

FENCE-RAIL.

SPECIFICATION forming part of Letters Patent No. 339,732, dated April 13, 1886.

Application filed July 1, 1885. Serial No. 170,399. (No model.)

To all whom it may concern:

Be it known that I, WILLIAM BILLINGS, of Dover, in the county of Bureau and State of Illinois, have invented an Improved Fence-Rail, of which the following is a specification.

The invention relates to that class of fences which are constructed partially or entirely of metal; and its special object is to make what constitutes the rails or takes the place thereof with as little expense as possible, but plainly visible and strong enough for all practical purposes.

Figure 1 of the drawings is a side elevation of a panel of one form of fence. Fig. 2 is a similar view of a modification. Fig. 3 is a detail view, in perspective, of a single rail, which will form an article of manufacture in agricultural stores, and be ready for farmers or consumers to put up on wood prepared by themselves.

In the drawings, A represents a flat metallic rail or wire, which has been preferably galvanized to make it weather-proof. I preferably make it from three to five eighths of an inch wide and eight feet long; but of course the dimensions are a matter of option. Like any other panel of fence, there may be any desired number of rails and any wished-for altitude.

In Fig. 2 of the drawings I show top and bottom rods, B B, of iron, between which these rails are arranged, the same being interwoven and looped together and about the rods, which are made fast to wooden posts C. Each rail has a hole, a, near the ends, so as to be readily

nailed to the wooden posts C C. It also has, 35 at equal intervals, bends a', which are made alternately in opposite directions, to form equal angles and allow the rails to loop together or pass around rods, as shown in Figs. 1 and 2 of the drawings.

The bends a' in the rail are given by a bending-machine, so that the user may easily weave them together by hand as he puts up his fence.

In Fig. 1 of the drawings I show the rails A not only nailed but battened to the posts, 45 and held at bottom to staples or keepers D, arranged alternately on opposite sides of boards E, made fast to the posts.

It will thus be perceived that I make a fence of cheap thin strips of metal interwoven together, stretched both vertically and horizontally between wooden or metallic supports. Besides its cheapness, utility, and durability, it is an ornamental fence, pleasant to the eye, and improving to the landscape.

Having thus described my invention, what I claim as new, and desire to protect by Letters Patent, is—

An article of manufacture, the described fence-rail, consisting of a flat metallic strip 60 with a hole near each end, and bends a', made alternately in opposite directions, substantially as set forth.

WILLIAM BILLINGS.
